UNITED STATES PATENT OFFICE.

JAMES W. BROWNE, OF BROOKLYN, NEW YORK.

IMPROVEMENT IN WEATHER-STRIPS.

Specification forming part of Letters Patent No. 143,324, dated September 30, 1873; application filed August 13, 1873.

To all whom it may concern:

Be it known that I, JAMES W. BROWNE, of Brooklyn, in the county of Kings and State of New York, have invented an Improved Weather-Strip, of which the following is a specification:

This weather-strip consists of a strip of vulcanized india-rubber and a narrower strip of felt or woolen cloth secured to it by sewing or some adhesive substance near one edge, so that the other edge may overlap slightly. The weather-strip thus made is intended to be applied, as hereinafter described, to the casings of windows, the frames of doors, and to crevices generally, wherever they may be. Dust, cold, and rain will thus be very effectually excluded from entering by this means.

In the accompanying drawing, Figure 1 is a face view of a portion of a window, having my improved weather-strip applied to it. Fig. 2 is a central vertical section of the same. Fig. 3 is a detail view of the strip detached.

Similar letters of reference indicate corresponding parts in all the figures.

A indicates the window-casing, and B C are the two sashes of the window. All are made in the usual way, and are represented merely to illustrate the application of my invention. D is a strip of vulcanized india-rubber, about half an inch wide, which, in connection with a strip or list, G, of soft flexible material, composes the weather-strip. This list is considerably narrower than the india-rubber, and may consist of cloth, felt, leather, or any other soft flexible material. It is secured to the rubber by parallel seams of sewing or by some adhesive substance, so that one of its edges is even with one of the edges of the india-rubber; therefore, the other edge of the rubber laps or overhangs the listing to the extent of the difference between their respective widths.

This weather-strip is designed principally for use on windows. It is applied to the window-casing, so that the overlapping edge of the rubber is in contact with the sashes, as shown more particularly in the lower portion of Fig. 2. It is arranged so near to the sashes that the aforesaid edge of the rubber will, in its normal condition, project beyond them, and, owing to this, it is sprung out of line with the rest when the sash is against it. Thus it is

made by its own elasticity to press constantly against the sash, and it will therefore preserve a very tight joint. It is fastened in place by tacks passing through it and entering the wooden casing. Double-pointed tacks may be chosen for this purpose, but the ordinary single-pointed kind is suitable also.

Owing to the yielding nature of the rubber the operation of the window-sashes will not be impaired by the application of the weather-strip. The soft list under the rubber will adapt itself to all irregularities which may be in the surface of the wood to which the strips are attached, and thus the strips are rendered effectual in a two-fold degree: First, because they prevent anything passing between themselves and the window-casing; and then, again, because they exclude anything from passing between the window-casing and its sashes. When the strips are employed to deaden noise the list is of the utmost value.

The weather-strip made thus is at once simple, and, besides being very effective, possesses the great advantage of cheapness. It can be applied by any housekeeper, for the simple reason that a few tacks are all that is needed to fasten it in place.

For transportation and sale it is done up in rolls, and can be readily cut to the desired lengths for the various purposes to which it may be put. This feature alone, I think, should recommend it greatly, as it is the means of obviating waste, and brings it within the ability of any person to apply. It can be bent round curves and corners with the utmost ease, and therefore may be made to fulfil its purpose with extraordinary efficacy.

In nicely-finished work, where it is desirable to render the appearance as comely as possible, fancy moldings may be applied to cover the strips all but their operative edges, as I have illustrated in the drawing.

What I claim as my invention is—

The weather-strip, composed of the strip of vulcanized india-rubber and a narrower strip of felt or woolen cloth secured together, substantially as described, for the purpose set forth.

J. W. BROWNE.
